WILLIAM VICTOR PETERSON, OF MINNEAPOLIS, MINNESOTA, ASSIGNOR TO WYCKOFF, SEAMANS & BENEDICT, OF ILION, NEW YORK, A CORPORATION OF NEW YORK.

TYPE-WRITING MACHINE.

No. 876,393.

Specification of Letters Patent.

Patented Jan. 14, 1908.

Application filed May 5, 1905. Serial No. 258,931.

To all whom it may concern:

Be it known that I, WILLIAM VICTOR PETERSON, citizen of the United States, and resident of Minneapolis, in the county of 5 Hennepin and State of Minnesota, have invented certain new and useful Improvements in Type-Writing Machines, of which the following is a specification.

The present invention relates to tabulating devices for typewriting machines, wherein in the carriage is released at any point in its leftward traverse from the control of its escapement mechanism, is quickly advanced and is automatically arrested at a predetermined point or points.

Machines of the class referred to are provided with one or more stops on the carriage which are adapted to co-act with one or more stops on the framework of the machine.

20 When the carriage stop strikes the stop on the machine frame, the carriage sometimes rebounds and would be liable, if permitted to reengage with the escapement mechanism during such rebound, to stop at a wrong 25 position.

The main object of my invention is to cure this defect, and I do this by providing means for preventing rebound when the stops co-act, said means consisting preferably of an 30 independent catch or stop which is associated with the usual carriage stop.

To the above and other ends the invention consists in certain features of construction and combinations of devices hereinafter 35 fully described and particularly pointed out in the claims.

In the accompanying drawings, Figure 1 is a side elevation of so much of a type-writing machine and its tabulating mechanism as is 40 necessary to illustrate my invention; Fig. 2 is an enlarged top plan view of the series of denominational stops mounted on the machine frame and of a portion of the stop rack-bar on the carriage, a column stop and its 45 associated back stop or anti-rebound stop being shown mounted on said rack bar; Fig. 3 is an enlarged perspective view of an anti-rebound stop; and Fig. 4 is an enlarged 50 perspective view of a modified form of anti-rebound stop.

I have shown my invention as applied to a No. 6 Remington typewriter and to the tabulating mechanism usually associated with that machine, but it is to be understood 55 that the invention may be adapted to other

forms and styles of writing machines and tabulators.

In the drawings, 1 designates the base of the machine, 2 corner posts and 3 a top plate surmounting the latter. The paper carriage 4 is provided with wheels or rollers 5 which travel on parallel guide rails 6. A spring drum (not shown) is connected with the paper carriage and constantly tends to move it towards the left, this movement being controlled during the course of the writing by an escapement mechanism comprising a feed rack 7, mounted on spring-pressed arms 8 which are pivoted at 9 on the paper carriage, a pinion 10 with which said rack normally meshes, an escapement wheel 11 operatively connected with said pinion, and key controlled escapement dogs (not shown) which are adapted to alternately engage the teeth of said escapement wheel and give to 75 the carriage a step-by-step feed movement leftward across the top plate as long as the feed rack 7 and pinion 10 are in engagement.

Extending rearwardly from the carriage 4 are arms 12, one of which only is shown, said 80 arms supporting a column-stop rack-bar 13 which is toothed or notched on opposite sides to receive one or more bifurcated column stops 14, said stops being removable and adjustable to different positions on said 85 rack bar, the latter being graduated to correspond to the usual carriage scale. A series of denominational stops 15 are slidably arranged in a frame or housing 16 supported by a bracket 17 secured to the base 1 and extending upwardly in rear of the rack bar 13 with the stops 14 whereon the slideable denominational stops 15 are adapted to co-operate. Each denominational stop 15 is connected by a pin and slot connection with a 95 vertically disposed lever 18 pivoted at 19 in the bracket 17 and connected at its lower end to a horizontal push rod 20, arranged beneath the base of the machine. Each push rod 20 is provided with a restoring spring 21 100 and terminates at its forward end in a key button 22.

Each of the denominational stops 15 is formed with a shoulder 23 which is adapted to co-act with a universal bar 24 supported 105 by arms 25 pivoted at 26 on the bracket 17. The arms 25 are connected to a rocker arm 27 which, by a link 28, is connected with a lever 29 pivoted at 30 in a bracket 31 on the top plate 3. The forward or free end of the 110

lever 29 carries a shoe piece or lifter 32 which is adapted to swing the feed rack 7 upwardly about its pivots 9 when the rear end of the lever 29 is pulled down, as occurs when any one of the denominational stops 15 is moved forwardly in a known manner. When thus freed from the control of its escapement or letter space feed mechanism, the carriage will move forwardly across the top plate under the influence of the spring drum until the first column stop 14 at the right of the projected denominational stop 15 contacts with the latter. If at the start the distance between the co-acting stops is sufficiently great to allow the carriage during its movement to acquire considerable momentum, it is liable to rebound when the column stop strikes the denominational stop; and should the escapement rack 7 be permitted to reengage with the pinion 10 before the carriage or column stop again contacts with the denominational stop after the rebound, the carriage will be arrested one or more letter space distances to the right of the proper point.

To obviate the defect just described I provide means for preventing the rebound of the carriage, said means, as herein shown, being in the form of an anti-rebound or locking stop designated as a whole by the reference 33, as best shown in Fig. 3 of the drawings. The anti-rebound or locking stop 33 comprises a bifurcated plate-like portion 34, the arms 35 whereof are designed to engage with the notches or teeth of the rack bar 13, and a stop portion or spring arm 36 extending laterally of the portion 34 and suitably connected therewith, as by a rivet 37. I do not, however, desire to be limited to the particular construction of anti-rebound stop just described as other constructions of stop may be employed within the scope of my invention. One such is illustrated in Fig. 4, the stop 38 therein shown being composed of one piece, the bifurcated portion 39 and the stop portion 40 being formed from a single plate of metal.

The anti-rebound stop 33 is adjustably mounted upon the rack bar 13 and is removable therefrom in a manner similar to the column stop 14 with which it is associated, but of which it is entirely independent. The stop 33 is preferably placed upon the rack-bar to the left of and at such distance from a column stop that the free end of the stop portion 36 of the anti-rebound stop is far enough from the adjacent face of the column stop 14 to afford sufficient space for the entrance between them of the beveled forward end of the projected denominational stop 15, as best appears in Fig. 2.

The operation of the invention will now be explained.

The column stop 14 is shown in Fig. 2 as being engaged with the rack bar 13 at the point "48" on the rack bar scale, and the

anti-rebound stop or back stop 33 is shown engaged with the rack bar at the point "38" or ten spaces to the left of its associated column stop. Of course the point at which the stop 33 is placed will depend upon the length of its stop portion 36 and may be at a less or greater distance from its associated column stop than that specified. Suppose for the sake of illustration, that the carriage be positioned at a point corresponding to "25" 70 or "30" on the rack bar scale, and that while so positioned the finger button 22 of the fourth denominational stop 15 be pressed in. The motion imparted to the finger button or key 22 will be transmitted through the push 80 rod 20 and lever 18 to the fourth denominational stop 15 which will be projected or slid forward as indicated in Fig. 2. The shoulder 23 of said denominational stop will, in its forward movement, press against the universal 85 bar 24, swinging said universal bar forwardly about the pivot 26 and depressing the arm 27 which, through the link 28, exerts a downward pull on the rearward arm of the lever 29 and causes the lifter 32 on the forward end 90 of said lever to swing the carriage rack 7 upwardly about the pinion 10. As soon as the carriage rack is disconnected from its pinion the spring drum will draw the carriage leftward, the latter gathering momentum as it 95 proceeds, until the stop portion or spring arm 36 of the anti-rebound stop 33 contacts with the projected denominational stop 15, said stop portion, as indicated in Fig. 2, inclining rearwardly into the path of said projected denominational stop. As the carriage 100 continues its leftward movement after the contact of the stop portion 36 with the denominational stop, said stop portion will be pressed forward, it having sufficient spring or 105 give to permit of such forward movement, and will at the same time exert a retarding effect on the paper carriage 4 on which it is mounted. As soon as the free end of the stop portion 36 has passed the projected 110 denominational stop 15, it will spring rearwardly to normal position, and the parts are so arranged that almost simultaneously therewith the column stop 14 will contact with the projected denominational stop. 115 Under the conditions assumed the carriage will have acquired considerable momentum when the last mentioned contact occurs, despite the braking or retarding effect of the anti-rebound stop heretofore mentioned. 120 Consequently there will be some tendency on the part of the carriage to rebound, but this rebound is instantly checked by the engagement of the end of the part 36 with the left-hand face of the projected denominational 125 stop 15, said end, as clearly appears in Fig. 2, being at the moment in its normal position and rearward of the front edge of the projected denominational stop. The result is that the column stop is embraced closely by 130

the denominational stop and the anti-rebound stop, and the carriage is locked so that it cannot be moved a full letter space in either direction until the denominational stop is retracted.

5 It will be understood that whenever the column stops 14 are arranged on the rack bar 13 sufficiently far apart to cause rebound of the carriage as it passes rapidly or jumps 10 from one to the other during the operation of the machine in tabulating work, an anti-rebound or locking stop 33 may be arranged on the rack bar 13 in association with each of the said stops in the manner indicated in 15 Fig. 2, and rebound will thereby be obviated.

When the column stops are arranged upon the rack bar at comparatively short distances apart, the carriage in passing rapidly or jumping from one stop to the other does 20 not acquire momentum sufficient to cause it to rebound to an appreciable extent and anti-rebound stops or locking catches need not be in connection with such closely arranged column stops.

25 Various changes of construction, besides those hereinbefore specified, and in the arrangement of the parts may be made without departing from the scope of my invention.

What I claim as new and desire to secure 30 by Letters Patent, is:—

1. In a typewriting and tabulating mechanism, the combination of a carriage; a stop thereon; a stop on the frame of the machine; means for projecting one of said stops into 35 the path of the other stop and for releasing the carriage; and a third stop independent of and unconnected with both of said first named stops and adapted to engage one of said first named stops to prevent rebound of 40 said carriage.

2. In a typewriting and tabulating mechanism, the combination of a carriage; a stop thereon; a stop on the frame of the machine; means for projecting one of said stops into 45 the path of the other stop and for releasing the carriage; and an independently adjustable and separately movable stop adapted to engage one of said first named stops to prevent rebound of the carriage.

50 3. In a typewriting and tabulating mechanism, the combination of a carriage; a rack bar; a stop mounted on said rack bar and adjustable longitudinally thereof; a second stop; means for projecting one of said stops into the path of the other and for releasing the carriage; and a third stop mounted upon 55 said rack bar and adjustable thereon independently of said first named stop, said third stop being adapted to engage one of the other stops to prevent rebound of the carriage.

4. In a typewriting and tabulating mechanism, the combination of a carriage; a rack bar disposed longitudinally of said carriage; 60 a column stop adjustable along said rack bar;

an anti-rebound stop adjustable on said rack bar independently of said column stop; and another stop adapted to co-act, when the tabulating mechanism is operated, with the said column stop in one direction and with 70 said anti-rebound stop in the opposite direction.

5. In a typewriting and tabulating mechanism, the combination of a carriage; a stop thereon; a stop on the frame of the machine, 75 one of said stops being adapted to co-act with the other after the carriage has been released by the operation of the tabulating mechanism; and a third stop independent of both of the other two stops and unconnected with either, the construction being such that when the carriage is arrested by the co-action between the first named stops, one of the co-acting stops will be embraced between the other and said third stop. 80

6. In a typewriting and tabulating mechanism, the combination of a carriage; a stop thereon; a stop on the frame of the machine, one of said stops being adapted to be projected to co-act with the other when the carriage 90 is released by the operation of the tabulating mechanism; and a separate anti-rebound stop normally in the path of the projected stop, the construction being such that when the carriage is arrested by the co-action between the first named stops, one of the latter will be locked by and embraced between the other co-acting stop and the anti-rebound stop, one of the locking stops preventing motion of the locked stop in one direction and 95 the other of the locking stops preventing motion in the opposite direction. 100

7. In a typewriting and tabulating mechanism, three co-operating stops, one of said stops being adapted to be projected into the 105 path of the other two stops by the tabulating operation and being positioned when the carriage is arrested at the end of the tabulating operation so that movement of the carriage less than a letter space in either direction will 110 cause a contact between said projected stop and one of the other two stops, which two stops are adjustable independently of each other.

8. In a typewriting and tabulating mechanism, the combination of a carriage; a rack bar; a column stop adjustable thereon; an anti-rebound stop adjustable on said rack bar independently of said column stop; and a third stop adapted to enter the space between 115 said column stop and said anti-rebound stop so that movement of the carriage in either direction is prevented. 120

9. In a typewriting and tabulating mechanism; the combination of a carriage; a rack bar; a column stop adjustable thereon; an anti-rebound stop independently adjustable on said rack bar and disposed in advance of 125 said column stop; and a third stop adapted to be projected into the path of the other two 130

stops so that when the carriage is released during the tabulating operation said projected stop will first co-act with said anti-rebound stop and will thereafter co-act with 5 said column stop.

10. In a typewriting and tabulating mechanism, the combination of a carriage; a rack bar; a column stop adjustable thereon; an anti-rebound stop mounted on said rack bar independently of said column stop and in advance of the latter; and a third stop adapted to be projected into the path of the first named stops during the tabulating operation, so as to co-act with the anti-rebound stop to 15 move part of it out of normal position and thereafter to co-act with the column stop after the anti-rebound stop has returned to normal position.

11. In a typewriting and tabulating mechanism, the combination of a carriage; a rack bar; a column stop adjustable thereon; an anti-rebound stop having a spring arm and mounted on said rack bar independently of said column stop and in advance of the latter; 20 and a third stop adapted to be projected into the path of the first named stops during the tabulating operation so as to co-act with the spring arm of the anti-rebound stop to move said arm from normal position and thereafter 25 to co-act with the column stop after the spring arm of the anti-rebound stop has returned to normal position.

12. A detachable one-piece anti-rebound stop for the tabulating mechanism of a typewriting machine, comprising a plate having a bifurcated or notched portion for engaging teeth on the opposite sides of a rack bar mounted to travel with the paper carriage and a lateral anti-rebound portion connected with the plate and adapted to co-operate with a tabulator stop on said rack bar and another tabulator stop on the frame.

13. A detachable anti-rebound stop for the tabulating mechanism of a typewriting machine, comprising a bifurcated plate and a spring arm disposed laterally thereof and rigidly connected therewith, said anti-rebound stop being co-operative with two tabulator stops, one on the carriage of the 45 machine and the other on the machine frame, to stop the carriage at the end of a tabulating movement and to prevent rebound of said carriage.

14. A detachable anti-rebound stop for 55 the tabulating mechanism of a typewriting machine, comprising a bifurcated or notched plate-like portion adapted to engage with the teeth at opposite sides of the column-stop rack-bar of the tabulating mechanism; 60 and a spring arm or detent attached to said plate-like portion by a rivet, said anti-rebound stop being co-operative with two tabulator stops, one on the carriage of the machine and the other on the machine frame, to stop the carriage at the end of a 65

tabulating movement and to prevent rebound of said carriage.

15. In a typewriting and tabulating mechanism, the combination of a carriage; a rack bar; a column stop adjustable thereon; an anti-rebound stop having a spring arm and mounted on said rack bar independently of said column stop and in advance of the latter; and a third stop adapted to be projected into the path of the first named stops during the 70 tabulating operation so as to co-act with the spring arm of the anti-rebound stop, thereby exerting a retarding effect on the carriage, and thereafter to co-act with said column stop. 75

16. In a typewriting and tabulating mechanism, the combination of a carriage; an anti-rebound stop adjustable longitudinally of said carriage and adapted to prevent rebound of said carriage when the latter is 80 brought to a stop after it has been jumped or moved during the tabulating operation, said anti-rebound stop being provided with means for retarding the carriage as it nears the end of its movement. 85

17. In a typewriting and tabulating mechanism, the combination of a carriage; a column stop adjustable longitudinally thereof; an anti-rebound stop adjustable longitudinally of said carriage independently of said column stop; and a third stop adapted to be projected into the paths of the first named stops during a tabulating operation so as to move part of the anti-rebound stop from 90 normal position and retard the carriage before co-acting with said column stop. 95

18. In a typewriting and tabulating mechanism, the combination of a carriage; a rack bar thereon; a column stop adjustable along said rack bar; an anti-rebound stop separate 100 from said column stop and also adjustable along said rack bar, said anti-rebound stop having a spring arm; a third stop adapted to be projected into the paths of the other two stops so that in the tabulating operation of the machine said projected stop first bends or flexes the spring arm of said anti-rebound stop, then disengages from the latter permitting said spring arm to return to normal position, and thereafter contacts with said 105 column stop. 110

19. In a typewriting and tabulating mechanism, the combination of a carriage; escapement mechanism therefor; a rack bar on said carriage; a column stop adjustable along said rack bar; an anti-rebound stop separately adjustable along said rack bar and having a spring arm; a series of denominational stops; means for projecting any one of said denominational stops into the paths of the anti-rebound and column stops and for freeing the carriage from said escapement mechanism, the construction and arrangement being such that the projected denominational stop first contacts with the spring arm of the anti- 115 120 125 130

rebound stop, bending or flexing said arm, said denominational stop then releasing said spring arm permitting it to return to normal position, and thereafter said denominational 5 stop co-acts with said column stop to arrest the carriage, rebound of the latter being prevented by the end of the spring arm of said anti-rebound stop which is then in normal position and is adapted to engage with the

left-hand face of the projected denominational stop.

Signed at Minneapolis, in the county of Hennepin, and State of Minnesota this 26th day of April A. D. 1905.
